UNITED STATES PATENT OFFICE.

ALBERT J. MARSTON, OF WORCESTER, MASSACHUSETTS.

SURGICAL CHAIR.

SPECIFICATION forming part of Letters Patent No. 363,404, dated May 24, 1887.

Application filed November 15, 1886. Serial No. 218,846. (No model.)

To all whom it may concern:

Be it known that I, ALBERT J. MARSTON, of Worcester, in the county of Worcester and State of Massachusetts, have invented certain new and useful Improvements in Surgeon's Combined Chair and Table; and I do hereby declare that the following is a full, clear, and exact description of the same, reference being had to the accompanying drawings, forming a part of this specification, and in which—

Figure 1 represents a side view of my aforesaid combined chair and table when converted into a chair. Fig. 2 represents a front view of said chair, looking in the direction of arrow *a* in Fig. 1. Fig. 3 is a vertical longitudinal section through the chair, taken on line *c*, Fig. 2, looking in the direction of arrow *d*, same figure. Fig. 4 is a back view of the chair, looking in the direction of arrow *b*, Fig. 1. Figs. 5 and 6 are side and bottom views, respectively, of a part of the chair, hereinafter more fully described. Fig. 7 is a side view of my combined chair and table when converted into a surgeon's operating-table, one end thereof being shown by dotted lines slightly elevated, for the purpose hereinafter specified. Fig. 8 is a top or plan view of the table in position for gynecological operations, the extension-piece thereof being removed, 30 and the foot-rests shown drawn out ready for use when the patient is in the dorsal position, said figure also showing by dotted lines the extension-piece aforesaid applied to one side of the table, for treatment of patients when in the Sims position or lying upon the side; and Fig. 9 represents my combined chair and table folded up in compact form ready for storage or shipment.

My invention relates to adjustable operating chairs and tables for the use of surgeons and gynecologists, adapted to be converted into different positions, as required, and to be folded into compact form for storage or shipment.

Said invention comprises various improvements, hereinafter specified, in the construction of the surgeon's combined operating chair and table set forth in Letters Patent No. 327,570 of the United States, granted to me October 6, 1885.

To enable others skilled in the art to which

my invention appertains to make and use the same, I will now proceed to describe it more in detail.

In the drawings, the parts marked *e*, *f*, *g*, and *h* represent the principal frame-pieces of my combined chair and table, which are so constructed and hinged together as to admit of the easy adjustment thereof to bring the parts *g* *h* into any position required by the surgeon or gynecologist in operating upon his patients, being held when thus adjusted by means of the hinged supporting bail-braces *i* *j* and adjustable supporting-brace *k*, also hinged, the latter and the bail-brace *i* at the points *k'* and *i'*, respectively, to the long frame *e*, and the bail-brace *j* at *j'* to the frame *g*. The brace *k* is detachably connected at its upper end when in use to the outer end of the hinged part *h*, and the lower ends of the bail-braces are held in their adjusted positions against the upper edges of one or the other of the cross-pieces *l*, *m*, *n*, and *o*, or in the notches *p* *q*, as the case may be, the shoulders and notches *l* *m* *p* *q* serving to hold the brace *i*, and the shoulders *n* *o* the brace *j*, as shown in the drawings. Said bail-braces *i* *j* are prevented from slipping out of their respective holding-notches by the parts *r*, formed upon or secured to their respective places; and to further insure the braces being held in their adjusted positions a hinged device consisting of the parts *s* *s'* may be employed. Said device is arranged upon the inside of one of the arms of frame *f*, and is constructed and operated in the following manner: The upper end of the main part *s* is fork-shaped and receives the pointed end of the part *s'* therein, as shown in Figs. 3 and 5, and said parts are so fulcrumed in relation to each other that when the lower end of the part *s* is depressed or pushed inward by pressing upon the outer end of its projecting part *s'* the upper end of the part *s'*, which is hook-shaped, is also moved inward, away from the bottom of the bail-brace, thus admitting of the removal of the latter when in the position shown in Figs. 1 and 3. The same operation causes hooks formed on the main part *s* (opposite to each shoulder and notch) to be also depressed or moved back therefrom to release the bail-brace when held in any of said places. The position of the parts *s* *s'* when depressed, as

aforesaid, is shown in Fig. 5 of the drawings. Upon the pressure being removed from the projection s^2 the aforesaid parts s s' are forced back into their normal positions (shown in Fig. 3) by means of a suitable spring, s^3 , fastened to frame f , which bears against a projecting pin, s^4 , on the part s . (See Fig. 6.)

The purpose of employing two jointed and hinged pieces, s s' , as aforesaid, is to obtain less motion of the lower end of the part s in moving back the holding-hooks to release the bail-braces than would be necessitated by a longer leverage. I do not limit myself, however, to the construction described, as the same result may be effected by employing only one piece, hinged at its upper end above the highest holding-shoulder on the frame f . A like device may be employed in connection with the holding-shoulders n o on the frame e , and a greater or less number of bail-brace holding notches and shoulders may be employed on the frames e f than shown, if desired.

The supporting-brace k consists of a skeleton frame, (see Figs. 2 and 4,) having an extension rod or bar, k' , fitted to work up and down in the central part, k^2 , of said skeleton frame, as shown by Figs. 4 and 7. The upper end of the rod or bar k' is provided with a horizontal opening, through which a spring-bolt, t , fastened to the front end of the part h , may be passed to fasten the parts together when in use, as shown in the drawings.

In adjusting the combined chair and table to any desired position, the rod or bar k' is slipped up or down in the part k^2 , and after adjustment fastened by means of an ordinary set-screw, u , and nut v , the rod or bar being clamped tight against the part k^2 by turning up the nut v , as usual in such cases.

The frames g h may be fastened near the hinged point thereof, so that they may be held from moving out of position when used as a chair, by means of a hook, w , hinged to the frame g , and adapted to engage with a projection on a holding-plate, x , fastened to the cross-piece n of frame e . Said plate may also be extended a short distance below said cross-piece n , to serve as a stop to prevent the hinged bracket k from swinging in beyond said point when detached at its upper end from the frame h .

The part marked y represents an extension-frame for increasing the length of frame e when required. It is of more especial advantage when the combined chair and table is converted into an operating-table such as illustrated in Fig. 7. When converted into a chair, it is not essential, and may be used or not, as preferred, in the latter instance it serving merely the purpose of ornamentation to impart a more finished appearance to the back of said chair, rather than usefulness, as the head of the person sitting in the chair comes beneath said extension-frame, and it therefore does not serve as a support therefor.

In using the combined chair and table for gynecological operations the extension y is removed from the end, as shown in Fig. 8, and

in place thereof are used foot-rests z z' , or said extension applied to one side of the end of the table, according to the position that the patient is required to occupy under treatment—as, for instance, if required to occupy a dorsal position, said position is maintained by placing the heels against the curved parts z z' of the foot-rests to obtain the desired support for the legs, while if said patient is required to be placed in the Sims position or upon the side, the extension being fastened to the side of frame g , as shown by dotted lines in Fig. 8, serves as a support in this position.

The extension y may be securely fastened in either of the positions previously described by passing a bar, y' , (secured to the back side thereof, and provided with a forked end) through a loop, y^2 or y^3 , fastened to frame g , then passing the forked end over a thumbscrew, y^4 , and turning the nut y^5 thereof up tight against said forked end, as best shown in Fig. 4. In addition to the aforesaid fastening, the abutting side of the extension is provided with dowels, (see dotted lines,) which fit into openings y^6 , made in the side of frame g .

The foot rests z z' are fitted to slide in suitable guides, z^2 , fastened to the under side of said frame g , as shown in Fig. 4, so that they may be readily drawn out and pushed back by hand, as required. The inner end of each foot-rest is provided with a suitable stop, z^3 , to prevent their being drawn entirely out of their holding-guides.

In Fig. 9 I have shown my combined chair and table folded up ready for storage or shipment. When thus folded, it is obvious that the same may be conveniently transported from one place to another, being not only light in weight, but also occupying but little space in comparison to others now in use not made in accordance with my inventions. Said combined chair and table is susceptible of being converted into various other forms than those shown and described; but it will be unnecessary to illustrate or specify said additional manipulations to make clear the nature of my improvements.

The frames g h and extension y may be upholstered, as desired, with any material suitable for the purpose.

What I claim as new, and desire to secure by Letters Patent, is—

1. The back-frame e , bail-brace i , hinged to the upper end of said frame, frame f , having one or more supporting-shoulders upon the upper side thereof to receive the bottom of said bail-brace i , and an adjustable device arranged on one of the legs of frame f for holding the bail-brace in said notches, comprising a hinged lever provided with hooks or projections upon the upper side thereof, adapted to engage with and hold the bottom of the brace, also provided with means for forcing said lever toward the holding-notches aforesaid, and means whereby it may be forced back therefrom, in combination with frame g , hinged at the upper end to the upper end of frame e ,

frame *h*, hinged to the lower end of frame *g*, and adjustable means connected with the outer end of frame *h* and the bottom of frame *e* for supporting said outer end of frame *h*, substantially as shown and specified.

2. An adjustable device arranged on one of the legs of the back-supporting frame *f* for holding the bottom of the bail-brace *i* in the notches formed in the top side of said frame, comprising a hinged lever provided with hooks or projections upon the top side thereof adapted to engage with and hold said bottom of the bail-brace, means for forcing said lever toward the notches and bail-brace, and means whereby it may be forced back therefrom to release said bail-brace, substantially as shown and specified.

3. In a surgeon's combined operating chair and table, the extension-frame *y*, provided with the projecting rod or bar *y'* upon the under side thereof, fork-shaped at its extremity, also provided with two or more dowels upon its abutting edge, in combination with the frame *g*, provided with the openings *y*⁶ in the end and side edges thereof, also with the holding-loops *y*² *y*³, and the fastening-screw and nut *y*⁴ *y*⁵, or their equivalents, whereby said extension-frame may be fastened upon the end or one side of frame *g*, substantially as and for the purposes set forth.

4. In a surgeon's combined operating chair and table, the extension-supporting brace *k*, hinged at the bottom to the lower end of the back-supporting frame *e*, and provided with the extension-bar *k'*, fitted to slide longitudinally in the central part of said brace, also provided with the set-screw *u* and nut *v*, or their equivalents, for fastening the aforesaid rod or bar after adjustment to the body of the brace, in combination with the frames *e f g h*, bail-braces *i j*, and means for fastening the upper end of said brace *k* to the front end of frame *h*, said frames being hinged together, and the bail-braces hinged to the frames *e* and *g*, respectively, the latter also being supported and held in notches or shoulders formed in the top surfaces of the frames *e* and *f*, substantially as shown and specified.

5. Means for fastening the hinged frames *g h* to frame *e*, when the several parts are converted into a chair, consisting of the hook *w*, hinged to the bottom of frame *g*, or near where the frames *g h* are hinged together, and plate *x*, fastened to the cross-piece *n* of frame *e*, having a projection above said cross-piece for the hook *w* to engage with, and projecting below the cross-piece to form a stop for the hinged brace *h* to strike against when detached and swung down, in combination with the frames *e f g h* and bail-braces *i j*, all constructed, arranged, and hinged substantially as shown and specified.

6. A surgeon's combined operating chair and table, comprising, in combination, the top frames, *g h*, hinged together, the long supporting-frame *e*, hinged at its upper end to the outer end of frame *g*, and provided with one or more bail-brace-holding notches upon its upper side, the back-supporting frame *f*, hinged at one end to frame *e* at about its center, and provided with one or more bail-brace-supporting notches upon its upper side, bail-braces *i j*, hinged, respectively, to frames *e* and *g*, the front extension-brace, *k*, hinged to the bottom of long frame *e*, also provided with means for fastening the upper end thereof to the front end of frame *h*, and for fastening its extension part to the body or main part of the brace after adjustment, means for fastening the hinged frames *g h* to the frame *e* when the various parts are converted into a chair, adjustable means for holding the bottom of bail-brace *i* in the supporting-notches in frame *f*, the adjustable extension-frame *y*, provided with means for fastening the same to the end or one side of frame *g*, and foot-rests *z z*, provided with means for guiding and controlling the movements thereof in drawing out and pushing back the same from and toward the frame *g*, all constructed and arranged to be adjusted and operated substantially as shown and specified.

ALBERT J. MARSTON.
